United States Patent

Des. 235,513
Patented June 24, 1975

235,513

JEWELRY BOX

Glen A. Greer, 7416 NW. 7th 73127, and Robert W. Boutz, 5530 Woodbrier 73122, both of Oklahoma City, Okla.

Filed Apr. 11, 1973, Ser. No. 350,076

Term of patent 14 years

Int. Cl. D9—03

U.S. Cl. D9—223

FIG. 1

FIG. 2

FIG. 3

FIG. 4

FIG. 5

FIG. 6

FIG. 1 is a top plan view of a jewelry box showing our new design;

FIG. 2 is a front elevational view;

FIG. 3 is a right side elevational view;

FIG. 4 is a left side elevational view;

FIG. 5 is a rear elevational view;

FIG. 6 is a bottom plan view;

FIG. 7 is a rear perspective view of the jewelry box in an opened condition; and

FIG. 8 is a front perspective view thereof.

We claim:

The ornamental design for a jewelry box, substantially as shown and described.
